UNITED STATES PATENT OFFICE

149,250

DESIGN FOR AN ALPHABET FOR FORMING MONOGRAMS OR THE LIKE

Michael Chernow, New York, N. Y.

Application November 26, 1946, Serial No. 135,093

Term of patent 14 years

(Cl. D64—12)

To all whom it may concern:

Be it known that I, Michael Chernow, a citizen of the United States and residing at New York, in the county of New York and State of New York, have invented a new, original, and ornamental Design for an Alphabet for Forming Monograms or the like, of which the following is a specification, reference being had to the accompanying drawings, forming part thereof, and in which

Fig. 1 is a plan view of an alphabet for forming monograms or the like showing my new design, and

Fig. 2 is a perspective view of the letter O for the purpose of disclosing a third dimension and

which is typical of the remainder of the letters of the alphabet.

I claim:

The ornamental design for an alphabet for forming monograms or the like, substantially as shown and described.

MICHAEL CHERNOW.
